Primary Examiner — Sanjeev Paul

(57) **CLAIM**

The ornamental design for a float and strap for eyewear, as shown and described.

DESCRIPTION

FIG. 1 is a front view of the float and strap for eyewear in a first configuration, showing the new design;

FIG. 2 is a rear view of the float and strap for eyewear in the first configuration, showing the new design;

FIG. 3 is a top view of the float and strap for eyewear in the first configuration, showing the new design;

FIG. 4 is a bottom view of the float and strap for eyewear in the first configuration, showing the new design;

FIG. 5 is a perspective view of the float and strap for eyewear in the first configuration, showing the new design;

FIG. 6 is a perspective view of the float and strap for eyewear in a second configuration attached to the terminating ends of the tips of a pair of glasses, showing the new design;

FIG. 7 is a perspective view of the float and strap for eyewear in the second configuration attached to the terminating ends of the tips of a pair of eyewear and being worn by a person, showing the new design; and,

FIG. 8 is a perspective view of the float and strap for eyewear in the second configuration attached to the terminating ends of the tips of a pair of glasses, wherein the float is illustrated floating in water, showing the new design.

The broken lines in FIGS. 6, 7, and 8 showing the glasses represent environmental subject matter and form no part of the claim. The broken lines in FIGS. 1, 2, 5, 6, 7 and 8 that appear on the float portion of the device represent the boundary lines and form no part of the claim.

“ATOLLAS” shown in broken lines and forming no part of the claimed design is a registered trademark of Tighe, Shea, first named inventor, whose address at the time of filing is 238 Rutledge Ave Charleston SOUTH CAROLINA 29403.
